UNITED STATES PATENT OFFICE

HARRY M. FULLER, OF SALT LAKE CITY, UTAH

SPARK PLUG

Application filed July 9, 1927. Serial No. 204,524.

My invention relates to spark plugs and has for its object to provide a new and efficient spark plug which will have a more intense spark.

5 A further object is to provide a spark plug which will fire all of the gases in the combustion chamber of an internal combustion engine with a hotter spark than has heretofore been accomplished.

10 A still further object is to provide a spark plug which will be provided with additional spark gaps which increase the intensity of the spark in the firing chamber.

15 A still further object is to provide a spark plug which will be provided with additional spark gaps within the core thereof and which will have a step-up coil in the core to intensify the spark.

20 These objects I accomplish with the device illustrated in the accompanying drawings in which similar numerals and letters of reference indicate like parts throughout the several views and as described in the specification forming a part of this application and pointed out in the appended claims.

25 In the drawings in which I have shown the best and most preferred manner of building my invention, Figure 1 is a section of a spark plug, showing the spark gap therein. Figure 2 is a view of a double spark gap provided in a spark plug. Figure 3 is a view of a tubular modification of Figure 2. Figure 4 is a section of a spark plug with a coil between the gap forming two equally spaced gaps between the ends of the coil and the ends of the central wires of the plug. Figure 5 is a side elevation of the coil. Figure 6 is an end view thereof. Figure 7 is a side elevation of the contact post.

30 This application is an improvement over my first invention and patent of January 18th, 1927, Serial No. 66,723, Patent No. 1,614,951, dated Jan. 18, 1927.

35 In the drawings I have shown the core of the spark plug as A, the metal casing as B, the retaining plug as C and the usual gaskets between the plug and casing. A core A is provided of suitable material, such as porcelain or other composition which will withstand heat and will insulate and has a central bore 1 therethrough. One end of the

said bore 1 is enlarged, as at 2, and is internally threaded. An electrode wire 3, having a flange 4 near one end thereof, is then placed through the core 1 and the flange 4 holds the wire in the hole and prevents it from being pushed too far through said hole and entirely closes and seals the hole. A threaded contact post 5 is then provided, having a flange 6 thereon and a larger threaded portion 7 on the opposite end thereof. The extreme end 55 of the said portion 7 is constricted to form a small contact post 8. The threads of the portion 7 are made to fit in the threaded portion in the enlarged bore 2 of the core A. Between the end 8 of the post 5 and the end of the wire 3 I provide a coil of wire 9 which coil is of large enough diameter to fill the hole or bore 2 and so that when the wire 3 and the plug 5 are in place the ends of the coil 9 surround the extreme ends of the wire and plug 60 so that a spark in bridging the gap between them will jump to all sides alike as they are centered therearound.

65 Some modifications of the device may be made as shown in the drawings and instead of using a coil 9, a solid plug 10 may be inserted between the wire 3 and the plug 5, as shown in Figure 4. The inner end of the post 5 may also be extended longer and a spark gap be made between the ends of the 70 port 5 and the wire 3, making a simple single gap therebetween, as shown in Figure 2.

75 Other modifications may be made, as shown in Figure 3, where a threaded cylindrical tube 11 is screwed into the core in place of the coil 9, thereby providing two spark gaps, the same as shown in Figure 1, but with a cylindrical tube to bridge the gap and to carry the current from the post 5 to the wire 3. The spark gap is then from the post 5, to the 80 tube 11, to the wire 3 and the firing gap is between the wire 3 and the common spark wire 12 on the metal casing B.

85 These slight modifications may be made in the invention without departing from the 90 scope of the claims, the main invention being in the two spark gaps within the core of the plug, thereby intensifying the spark.

95 Having thus described my invention, I desire to secure by Letters Patent and claim: 100

1. In a spark plug the combination of a porcelain core, having a longitudinal central bore therethrough with one end of said bore of larger diameter than the other and with internal threads therein; a wire passed through said small bore; a flange on one end of said wire adapted to prevent the wire from coming out of said bore; a contact post having one end larger than the other and threaded to fit into said threaded portion of said bore; a coil of wire adapted to be placed within the larger diametered bore of said core with the lower end entirely surrounding said wire but not touching it by contact, and with the top end of said coil entirely surrounding the contact post but not in contact therewith so that when placed the coil is spaced from said wire and said contact post making two spark gaps therebetween.
2. In a spark plug the combination of a metal casing adapted to hold a core therein; a core to fit therein being centrally bored with two diametered holes in alignment therewith; a contact wire on said metal casing; a wire through the smaller bore of said core spaced from said contact wire; a coil carried in said bore of said core surrounding but not touching said wire; a closure and contact post secured in the top end of said core with the lower end within the circle of said coil but not contacting therewith; and means to connect wires therewith.

In testimony whereof I have affixed my signature.

HARRY M. FULLER.
